UNITED STATES PATENT OFFICE.

WILLIAM H. MUZZY, OF DAYTON, OHIO, ASSIGNOR TO THE NATIONAL CASH REGISTER COMPANY, OF DAYTON, OHIO, A CORPORATION OF OHIO, (INCORPORATED IN 1906.)

CASH-REGISTER.

1,158,537.

Specification of Letters Patent.

Patented Nov. 2, 1915.

Application filed October 7, 1907, Serial No. 396,331. Renewed February 13, 1915. Serial No. 8,072.

To all whom it may concern:

Be it known that I, WILLIAM H. MUZZY, a citizen of the United States, residing at Dayton, in the county of Montgomery and 5 State of Ohio, have invented certain new and useful Improvements in Cash-Registers, of which I declare the following to be a full, clear, and exact description.

This invention relates to improvements in 10 cash registers and has more particular relation to improvements in registers for ejecting check or value tokens.

The object of the invention is to provide 15 a registering mechanism in combination with check ejecting devices; the whole to be controlled by the insertion of coins, whereby suitable value tokens will be automatically ejected and the value of such tokens registered by the operation of the 20 machine.

With this and incidental objects in view, the invention consists in certain novel features of construction and combinations of parts, the essential elements of which are set 25 forth in appended claims and a preferred form of embodiment of which is hereinafter specifically described with reference to the drawings which accompany and form part of this specification.

30 Of said drawings: Figure 1 represents a central transverse section through the machine. Fig. 2 represents a detail perspective view of one of the coin trays. Fig. 3 represents a rear elevation of the machine 35 with the back of the casing removed. Fig. 4 represents a detail perspective of one of the contact plates; and Fig. 5 represents a detail transverse section through the registering mechanism.

40 Described in general terms the machine comprises a plurality of counter balanced levers, each being adapted to be operated by a coin of certain denominational value. Each coin deposited rocks its lever far 45 enough to form a circuit through an electric motor which will continue the movement of the lever to actuate the coin display and registering mechanism and eject a check or checks of the value of the coin inserted.

50 *Operating mechanism.*—The casing 1 in the present instance is provided with three coin chutes 2 adapted to receive five, ten and twenty-five cent pieces respectively. Upon depositing a coin of any of the above named

denominations in its respective chute 2, it 55 will slide through and rest upon a coin tray 5 secured to the end of a lever 6 and thus rock said lever. The downward, rearward and upward arms of the levers 6 are numbered 7, 8, and 9 respectively. It is to be 60 understood that there is one of these counter balanced levers, which are pivoted upon a transverse shaft 5^a, for each chute 2, and that each lever is provided with a suitable counter-balance 8^a. After a coin has been 65 inserted a lever will be rocked to the position shown by the dotted lines in Fig. 1 with the rear arm 8 in contact with one side of the metallic plates 12 secured to and projecting forward from an insulated plate 13 70 attached to the casing of the machine. As soon as the arm 8 touches the plate 12 a circuit is made from a battery 14 through wire 15 to the binding post 16, plate 12, arm 8, shaft 5^a, wire 17 to the binding post 18 75 through the motor 19, and thence from a binding post 20 through wire 21 back to the battery 14. The shaft 22 of the motor is equipped with a worm 23 which revolves a worm gear 24 secured to one end of a trans- 80 verse shaft 25. Adjacent to the downwardly extending arm 7 of each counter balanced lever is a two arm lever 26 whose arms 27 and 28 are diametrically opposite each other. The levers 26 are secured to the shaft 25, so 85 that the arms 27, (Fig. 1,) engage pins 29 extending laterally from the arms 7 of the counter balanced levers when the latter are moved to the position shown by dotted lines in said figure by the weight of a coin. The 90 arm 8, which is flexible, moves up the inclined side of its plate 12 to continue the contact. By the time arm 27 has passed out of engagement with its pin 29, the arm 8 will have passed above the plate 12 thereby breaking the circuit but the momentum of the motor will be sufficient to rotate the shaft 25 through the worm 23 and the worm gear 24 until the said shaft is stopped by the right hand arm 28, Fig. 3, engaging with 100 a friction spring 30 attached to the side of the casing 1. As the shaft 25 is given only a half revolution upon each operation of the machine it will be seen that the arms 27 and 28 of the levers 26 will alternately contact with the pins 29 projecting from the arms 7 of the counter balanced levers when the latter have been brought into the path 105

of said arms by the weight of inserted coins. The displaced lever is returned to normal position by a spring 35 controlled by a suitable dash pot 31^a as hereinafter described. 6 Each plate 12 is inclined at such an angle that, as the arm 8 ascends it will ride upon one side of said plate and as it descends it will ride down the opposite side which is insulated thereby preventing the motor 19 10 from being energized as the frame is returned. The arm 8 returns to its normal position when it passes free of the lower end of the plate 12.

Registering mechanism.—While the registering mechanism shown in the drawings is old and well known in the art, it is to be understood that the invention is not to be limited to this particular type of mechanism, as any of the other well known types may be 20 employed.

Referring to Figs. 1 and 3 it will be seen that adjacent to each counter balanced lever and mounted upon the same shaft is an upward extending arm 31 provided at its upper end with an elongated slot 32 into which enters a pin 33 projecting from a slide 34, each arm and slide being held in a retracted position by a spring 35. Extending upward from each slide 34 are two projections 36 between which is mounted the rear end of link 37, the forward end resting upon a transverse rod 38. Projecting laterally from each vertical arm 31 is a pin 39 which is arranged to be engaged by the upright arm 9 of the counter balanced lever as the latter is rocked by the previously described motor mechanism so that the arm 31 will also be rocked carrying with it its slide 34 and link 37. The initial movement of the lever by a coin 40 does not operate the arm 31 but only brings the arm 9 and pin 39 together. Each link 37 is provided with a shoulder 40 and a recess 41, the former engaging a rod 38 as the link is carried forward by its slide thereby raising the forward end of the link so that a rod 42 mounted in the lower ends of vertical arms 43 will enter the recess and carry said rod and arms the rest of the movement of said link. While the links 37, when operated, are given a definite movement, the recesses 41 being different distances from the rod 42 will give the latter a differential movement. The arms 43 are loosely mounted upon a transverse shaft 44 and are held 55 in contact with pins 45 projecting from the casing 1 by springs 46. The left hand arm 43, (see Fig. 3,) is provided with a rack segment 47 having teeth 48 at its upper edge that mesh with a pinion 49 loosely mounted 60 upon a shaft 50. Secured to this pinion is an arm 51 which carries at its outer end a pawl 52 which is spring pressed into engagement with a ratchet wheel 53 attached to one end of a short sleeve 54, to the other 65 end of which is secured a cents registering

wheel 55 with numerals from 0 to 95 in multiples of five. The pawl 52 drives the ratchet wheel in one direction, but rides idly over the same in the opposite direction. As the cents registering wheel moves from 95 to 0, 70 a pin 56 projecting from a spring pressed pawl 57 secured to the cents wheel will enter a cut out portion 58 of a stationary disk 59 thereby allowing said pawl to engage with a tooth of a ratchet wheel 60 secured to the 75 units of dollars wheel to advance it one space, after which the pawl 57 will be cammed out of engagement with the ratchet wheel, all of which is well known in the art and needs no further description here. At 80 attached to one side of each of the registering wheels is a star wheel 55^a with which a spring pressed pawl 56^a engages to prevent any accidental displacement or over rotation of same. The top of the casing 1 is 85 hinged as at 61 and is provided with a glass covered opening 62 through which the amounts on the adding wheels may be seen. This top is provided with a hinged lid 63 which is normally locked in position to cover the opening 62 so that only an authorized person may read the amounts on the adding wheels. The counter may be turned to zero in any well known manner.

Check ejecting devices.—A plurality of 95 tubes or receptacles 64 corresponding to the number of coin chutes 2 are mounted in the upward forward part of the casing, and each contains a number of checks 65 which are arranged to be ejected into a receptacle 66 secured to the front of the casing by the following described mechanism: Each slide 34 of the registering mechanism is provided with a narrow forward projection 67 which is supported by a guide 68 suitably secured to the casing. The projection 67 of the five cent slide normally rests in a recess formed on the back of the tube 64 and when moved forward ejects a single check from the first tube, while the ten and twenty-five cent slides are provided with enlarged heads 68^a which, when said slides are operated, eject two and six checks respectively, an extra check being given as an inducement for the customer to spend twenty-five cents. A shield 69 is attached to the front of the casing to prevent the withdrawal of checks without an operation of the machine. 110 115

Coin display.—Without some device to display the amount deposited, unscrupulous persons could manipulate the machine by inserting slugs or depositing a coin in a chute of higher denomination, and in order to overcome this method of manipulation the following described mechanism has been devised: Pivoted to the under side of each coin tray 5 is an arm 70 which is held in contact with the tray by a leaf spring 71. Upon depositing a coin in one of the chutes 2 the counter balanced lever corresponding 120 125 130

thereto will be rocked into the dotted line position shown in Fig. 1, where it will be temporarily arrested by the upright arm 9 of said lever contacting with the pin 39 of the vertical arm 31. As the shaft 25 starts to revolve one of the arms 27 will contact with the pin 29 projecting from the downward extending arm 7 of the lever and rock the latter. During the first part of this movement the arm 70 will engage with a bevel lug 72 attached to the upper end of an arm 73 extending upward from a plate 74, which is pivotally mounted upon a transverse shaft 75, and thus rock the arm 73 forward and the plate 74 downward against the tension of coil springs 76, (see Fig. 3,) surrounding the shaft 75. This rocking of the plate 74 will deposit the displayed coin into a locked receptacle 77 mounted in the lower part of the casing. As the coin tray carried by the arm 6 continues its downward movement the arm 70 will pass the lug 72 and the plate 74 will then spring back into the position shown in Fig. 1, after which the coin on the tray will slide onto the plate 74 beneath the glass covered opening 78 in the casing. Partitions 79 extend from the casing to the plate 74 and thereby form compartments for the different coins. As the lever is returned toward its normal position through means of the spring 35 drawing the arm 31 back to normal position, the arm 70 will wipe by the lug 72 without moving the plate 74. The arm 6 of said frame contacts with a rod 80 and limits the return movement of the frame.

In a great many establishments during the different seasons of the year extra help is employed to take care of certain lines of business, such as soda fountains in drug stores, and as these positions are only temporary, the proprietor finds it difficult to hire honest, capable and efficient employees. With a type of machine as herein described this difficulty is removed to a great extent, if not wholly, as the employee does not handle the money and has only to attend to the delivering of the goods. By holding the clerk responsible for any shortage that may occur between the amount shown on the adding wheels and the amount in the cash receptacle, he will be constantly on the alert to detect any attempt at manipulation of the machine.

While the form of device here shown and described is admirably adapted to fulfil the objects primarily stated, it is to be understood that it is not desired to confine the invention to the one form of embodiment here disclosed, for it is susceptible of embodiment in various forms, all coming within the scope of the claims which follow.

While I have shown in the present drawings an electric motor for automatically operating the machine, it will be readily under-

stood that any suitable form of motor, such for instance as a spring motor, may be employed without departing from the spirit of this invention. It will also be understood that instead of a registering mechanism, I might with equal facility employ another form of accounting device, such for instance as a printing mechanism. It will further be understood that the registering mechanism might be altogether independent of the check ejecting device, in which event the register will of course indicate the exact amount of coin which has been placed in the machine for any purpose, either as a cash receptacle or a cash register.

By providing suitable partitions in the drawer 77, the coins of different denominations may be kept separate and the proprietor thus enabled to determine whether any coins have been improperly inserted in the wrong slots in the machine.

What is claimed is:—

1. In a machine of the class described, the combination with a lever constructed to be actuated by a coin, of a check delivering device including an arm positioned to be operated by said lever, a driving motor, connections from said motor constructed to drive said lever after its coin actuated movement, and means whereby the motor is started by said coin controlled lever movement.

2. In a machine of the class described, the combination with a registering device, of a plurality of check delivering mechanisms, having connections to operate said registering device to different extents, a plurality of levers constructed to be actuated by deposited coins, a motor and a driving element actuated thereby and constructed to actuate said coin actuated levers, and connections from each coin actuated lever to the corresponding check delivering mechanism.

3. In a machine of the class described, the combination with a registering device, of a plurality of check delivering mechanisms having connections to actuate said registering device to different extents and each including a lever, a plurality of levers constructed to be actuated by deposited coins and positioned to operate said check delivering levers, a motor, and a connection therefrom positioned to engage any of the coin actuated levers after their coin actuated movement and to operate them and the check delivering mechanisms.

4. In a machine of the class described, the combination with a registering device and an operating frame therefor, of a plurality of check delivering mechanisms each including a lever, arms connected to said check delivering mechanism, and positioned to engage said operating frame, a plurality of levers constructed to be moved by deposited coins and positioned to engage said check delivering levers, a motor, and a connection

- therefrom positioned to engage and operate said coin moved levers after their coin actuated movement.
5. In a machine of the class described, the combination with a registering mechanism and an actuating frame therefor, of check delivering mechanisms each including a lever and having connections to move said actuating frame to different extents, a plurality of levers constructed to be actuated by deposited coins, and a motor having connections to drive said check delivering levers, with means whereby said motor is started by any of said coin actuated levers.
10. In a machine of the class described, the combination with a registering device and check delivering mechanisms having connections to actuate said registering device to different extents, of a main operating device, and elements, constructed to be actuated by deposited coins and when so actuated to connect said motor selectively to said delivering mechanisms.
15. In a machine of the class described, the combination with a check receptacle, a motor, a source of electrical energy, a counter-balanced lever moved by the weight of a coin to close a circuit through the motor, and means connected to the motor to continue the movement of the lever to eject a check from said receptacle.
20. In a machine of the class described, the combination with a registering device, and a plurality of check or token delivering mechanisms, of devices operated by deposited coins, a motor, and connections whereby said coin operated devices impart movement from said motor to said registering device, and to said delivering mechanisms.
25. In a machine of the class described, the combination with a registering device and a plurality of check or token delivering mechanisms, of a motor, and elements actuated by deposited coins serving selectively to connect said motor to said registering device and to said delivering mechanisms.
30. In a machine of the class described, the combination with a registering device and an actuating element therefor, of check or token delivering mechanisms constructed to drive said actuating element to different extents, a motor, and elements constructed to be actuated by deposited coins and when so actuated to connect said motor selectively to said delivering mechanisms.
35. In a machine of the class described, the combination with a registering device and check or token delivering mechanisms having connections to actuate said registering device to different extents, of a main operating device, and elements, constructed to be actuated by deposited coins and when so actuated to connect said main operating device selectively to said delivering mechanisms.
40. In a machine of the class described, the combination with a registering device and a plurality of check or token delivering mechanisms and a single registering device common thereto and operated thereby to different extents, of devices having their operation controlled by deposited coins and serving to determine the movement of said delivering mechanisms.
45. In a machine of the class described, the combination with a plurality of check or token delivering mechanisms, and a single registering device common thereto and operated thereby to different extents, of a main operating device, and elements constructed to be actuated by deposited coins and when so actuated to connect said main operating device selectively to said delivering mechanisms.
50. In a machine of the class described, the combination with a registering device and check or token delivering mechanisms having connections to actuate said registering device to different extents, of a main operating device, and elements, constructed to be actuated by deposited coins and when so actuated to connect said main operating device selectively to said delivering mechanisms.
55. In a machine of the class described, the combination with a plurality of check or token delivering mechanisms and a single registering device common thereto and operated thereby to different extents, of devices having their operation controlled by deposited coins and serving to determine the movement of said delivering mechanisms.
60. In a machine of the class described, the combination with a plurality of check or token delivering mechanisms, and a single registering device common thereto and operated thereby to different extents, of a main operating device, and elements constructed to be actuated by deposited coins and when so actuated to connect said main operating device selectively to said delivering mechanisms.
65. In a machine of the class described, the combination with a plurality of check or token delivering mechanisms, and a single registering device common thereto and operated thereby to different extents, of a main operating device, and elements constructed to be actuated by deposited coins and when so actuated to connect said main operating device selectively to said delivering mechanisms.
70. In a machine of the class described, the combination with a plurality of check or token delivering mechanisms, and a single registering device common thereto and operated thereby to different extents, of a main operating device, and elements constructed to be actuated by deposited coins and when so actuated to connect said main operating device selectively to said delivering mechanisms.
75. In testimony whereof I affix my signature in the presence of two witnesses.
